UNITED STATES PATENT OFFICE.

CHARLES M. SPANGLER, OF EMPORIUM, PENNSYLVANIA.

BOILER-FUUE TOOL.

1,400,102.

Specification of Letters Patent. Patented Dec. 13, 1921.

Application filed August 10, 1921. Serial No. 491,224.

To all whom it may concern:

Be it known that I, CHARLES M. SPANGLER, a citizen of the United States, residing at Emporium, in the county of Cameron and 5 State of Pennsylvania, have invented certain new and useful Improvements in Boiler-Fuue Tools, of which the following is a specification.

This invention relates to tools for crimping or bending the ends of boiler flues which are expanded or rolled in the flue sheets, so 10 that the flue may be removed.

In my Patent No. 1,391,862, dated September 27, 1921, I have set forth and claimed 15 a tool which is adapted for bending the ends of those flues which are held by a flange or bead flattened against the face of the flue sheet. Not all flues are thus secured as many are expanded or rolled, without 20 being provided with a flange, to hold them in the flue sheet.

My present invention is particularly designed for crimping the projecting end of a flue which is held in the flue sheet by being 25 provided with an expanded end.

I have shown and described herein the same form of handle or lever, fulcrum jaw, and yoke disclosed in my Patent No. 1,391,862.

30 My present improvements relate to the improved nicking or crimping jaw, herein-after described, and its combination with the lever or handle, fulcrum jaw, and yoke, whereby there is provided a tool particu- 35 larly adapted for the use hereinbefore specified.

I am aware that means other than those shown may be employed for securing the yoke to the handle and lever and the bend- 40 ing jaw to the yoke, and I do not, therefore, limit myself to the specific features of the invention shown in the drawing and hereinafter described, except where recited in the claims.

45 In the accompanying drawings:

Figure 1 is a side elevation of the complete tool, illustrating how it is used on a flue which is expanded or rolled into the flue sheet;

50 Fig. 2 is an end elevation at the jaw end of the tool;

Fig. 3 is a detail perspective of the nicking or crimping jaw;

Fig. 4 is a detail cross section through the 55 fulcrum jaw;

Fig. 5 is a plan view of the handle or lever and fulcrum jaw; and

Fig. 6 is an end view showing how the expanded or rolled end of the flue appears after it has been nicked or crimped down. 60

As in my Patent No. 1,391,862, I employ a handle or lever 1 having a squared part 1^a provided with jaw 2 rounded or notched at 3 and terminating in rounded fulcrum 4.

The nicking or crimping jaw 5 has a 65 squared shank 5^a of the same width as the squared part 1^a and it rests against the latter, being held by a yoke 6 which embraces the squared parts 1^a and 5^a. A screw or fastening device 7 clamps the yoke 6 to the 70 squared part 1^a; a screw or fastening device 8 carried by the yoke serves to clamp the squared part 5^a to the yoke. Consequently the yoke 6 and jaw 5 may be adjusted as a 75 unit in relation to the handle 1, and, further, the jaw 5 may be adjusted within, or through the yoke 6.

The first adjustment described enables the yoke and jaw 5 to be set to the position generally required and then a finer adjustment 80 of the jaw 5 is obtained by loosening the screw 8 and shifting the jaw 5 inside of the yoke 6 and then tightening screw 8.

The jaw 5 has its nicking or crimping end sloped and offset from the jaw 2 as 85 shown at 9 to provide sufficient clearance to enable proper operation to be had on the projecting end of the flue. The jaw is provided with upwardly converging beveled parts 10 which meet in a sharp or chisel-like 90 nicking or crimping ridge or edge 11 which is the effective part of the jaw that engages the projecting end of the flue.

The end 12 of the jaw 5 is sloped backwardly so that it will not contact with the 95 flue sheet during the application of the tool and to permit the sharp edge 11 to take a firm bite on the extended end of the flue.

The flue appears at 13 in Fig. 1 with a projecting end 14 which lies beyond the 100 outer face of the flue sheet. The flue shown in Fig. 1 is of the expanded or rolled type wherein the projecting part 14 is not beaded or flanged against the face of the sheet.

Fig. 6 illustrates the appearance of the 105 projecting end 14 of the flue after it has been nicked and crimped by the tool.

The tool is operated as shown in Fig. 1, after suitable adjustment. The fulcrum 4 bears against the inside of the flue and the 110

nicking chisel-shaped edge 11 works against the outer face of the end 14 where it projects beyond the flue sheet.

The end 14 is crimped by operating the lever upwardly from the position shown in Fig. 1, then moving it to another position circumferentially of the end 14 to take a fresh bite on the latter. Another nick or crimp is thus made. The work thus progresses until the end 14 has been completely crimped as shown in Fig. 6 whereupon the flue may be readily removed from the flue sheet.

My tool affords an easily operated and convenient device for the purpose set forth without any danger of injuring the flue sheets.

I claim:

1. A boiler flue tool comprising a handle or lever having a rigid jaw provided with a fulcrum adapted to engage the inner surface of the flue which is to be removed, and a jaw adjustable lengthwise of the lever or handle for the purpose of setting it at the desired point, said jaw being provided with a chisel-like edge which extends lengthwise of said jaw and handle.

2. A boiler flue tool comprising a handle or lever having a notched jaw terminating in a fulcrum adapted to engage the inner surface of the flue which is to be removed, and a nicking or crimping jaw which is adjustable lengthwise of the lever or handle for the purpose of setting it at the point desired, said jaw being provided with a chisel-like ridge adapted to be disposed opposite the notch in the first-named jaw, said ridge extending in the direction of the length of said jaws.

3. A boiler flue tool comprising a handle or lever having a rigid jaw provided with a fulcrum adapted to engage the inner surface of the flue which is to be removed, and a nicking or crimping jaw which is adjustable lengthwise of the lever or handle, said jaw having its sides beveled and converging upwardly and terminating in a chisel-like ridge extending lengthwise of the jaws and is disposed in angular relation to the fulcrum jaw.

In testimony whereof I affix my signature.

CHARLES M. SPANGLER.
